UNITED STATES PATENT OFFICE.

ELLIS T. SILVIUS, OF INDIANAPOLIS, INDIANA, ASSIGNOR, BY MESNE ASSIGNMENTS,
TO THE McCASKEY REGISTER COMPANY, (INCORPORATED IN 1914,) OF ALLIANCE,
OHIO, A CORPORATION OF OHIO.

CREDIT-ACCOUNTING REGISTER.

1,135,214.

Specification of Letters Patent. Patented Apr. 13, 1915.

Application filed July 3, 1911. Serial No. 636,718.

To all whom it may concern:

Be it known that I, ELLIS T. SILVIUS, a citizen of the United States, residing at Indianapolis, in the county of Marion and 5 State of Indiana, have invented a new and useful Credit-Accounting Register, of which the following is a specification, reference being had to the accompanying drawings and to the letters and figures of reference 10 marked thereon.

The present invention relates to apparatus, the general characteristics of which are well known, being used by merchants for filing various kinds of papers for future 15 reference, and more particularly for systematically keeping accurate credit accounts, the invention having reference more particularly to devices for connecting the bill holding leaves or frames together that 20 constitute pivotally supported parts of filing cabinets, the leaves or frames being adapted to stand uprightly in normal position in echelon or to lie in prone position in the form of a rectangular pack.

25 The object of the present invention is to provide improved positive controlling means for the adjustable hinging connections with which the leaves or frames are provided, a further object being to provide adjustable 30 hinge controlling mechanism that will be simple and adapted to be cheaply constructed of the minimum numbers of parts.

A still further object is to provide adjustable hinge controlling mechanism that 35 will be adapted to be varied in proportion, so that the degree of stepping of the leaves in echelon may be varied in different cabinets, as may be desired.

The invention comprises the combination, 40 with bill holding leaves or frames provided with adjustable hinging connections, of novel controlling mechanism whereby the leaves or frames of the register or cabinet are caused to operate during pivotal movement of the leaves or frames, so that the latter shall be in echelon when in normal upright position or form a rectangular pack when in prone position; the invention consisting also in the parts and combinations 45 and arrangements of parts as hereinafter particularly described and claimed.

Referring to the drawings, Figure 1 is a front elevation of a credit accounting register or file cabinet constructed substan-

tially in accordance with the invention; 55 Fig. 2, a fragmentary sectional elevation approximately on the line A A in Fig. 1; Fig. 3, a fragmentary sectional elevation approximately on the line B B in Fig. 1 with the leaves or frames in prone position; Fig. 60 4, a fragmentary sectional elevation also on the line B B but with the leaves in different positions, as when a number are being moved; Fig. 5, a fragmentary vertical section approximately on the line C C in Fig. 65 1 with the leaves in different positions; Fig. 6, a fragmentary section as at the plane of the line B B with all the leaves arranged as when in movement; Figs. 7 and 8, fragmentary perspective views showing portions of 70 the frame parts as preferably constructed of built up members and provided with the improved hinge controlling mechanism; Fig. 9, a perspective view of one of the parts of the hinge controlling mechanism; Fig. 10, 75 a fragmentary sectional elevation on the plane of the line D D in Fig. 3 on an enlarged scale; Fig. 11, a fragmentary sectional elevation on the plane of the line E E in Fig. 5; Fig. 12, a perspective view of one 80 of the adjustable hinge parts; and Fig. 13, a fragmentary perspective view of two connected leaves or frames.

Similar reference characters indicate like elements or features of construction through- 85 out the drawings herein referred to.

The case of the register or filing cabinet may be variously constructed, as may be preferred, and suitably comprises a desk-like part 1 having a transverse rail 2 constituting a leaf or frame support in the upper rearward portion thereof from which extends a top or lid 3 on which the bill holding leaves or frames are supported when in prone position, a floor 4 extending 90 from the rail rearward to a back 5, which extends upward to a suitable height, and has sides 6 and 7 secured thereto and extending forwardly to or beyond the position of the rail 2.

100 A pair of pivot bearings 8 and 8' are secured upon the rail 2 for supporting a complete set of the bill holding leaves or frames comprising any suitable or desired number as 9, 10, 10', 10", all generally similar in 105 construction and provided with suitable clamps 11 or such devices as may be preferred for holding papers on the leaves or

frames in systematic order. Part of the hinging connections of the leaves having been described in my pending applications for Letters Patent, Serial No. 525,100 and No. 623,424, are herein only briefly referred to. The foremost leaf 9 is provided with a pair of pivots 12 and 12' which are movably connected with the pivot bearings 8 and 8'. The lower rearward portion of each one of the leaves, excepting the rearmost leaf 10'', is provided with hinging ears 13 and 13' having hinge pins 14 and 14' respectively. Each one of the leaves, excepting the foremost leaf 9 has a pair of hinge bars 15 and 15' mounted movably in the lower side portions of the leaf in the guide ways 16 and 16', suitable hinge bars being movable longitudinally with respect to the leaf and are provided with hinging ears 17 and 17' respectively, which are connected to the hinge pins 14 and 14' respectively of the next adjacent forward leaves. Each one of the leaves, excepting the foremost leaf 9, is provided with two bars 18 and 18' which are fixedly connected to the leaf and extend at the sides thereof beyond the plane of the normally lower end of the leaf, the bars being provided with gear teeth 19 and 19' respectively, which extend forwardly from the forward sides of the bars so as to constitute rack bars, said rack bars comprising parts of the present invention. A suitable number of segments or gear wheels 20 and 20' are provided for controlling the movement of the leaves with respect to the hinge bars, the segments being mounted on the hinge pins 14 and 14' respectively, the hinge pins being of sufficient length to extend outward beyond the hinging ears 13 and 13', the segments having gear teeth 21 and 21' thereon respectively, which are in mesh with the gear teeth 19 and 19' respectively. The segments 20 and 20' are provided with operating and controlling arms 22 and 22' respectively, so that the segments and arms constitute levers, the arms being provided with wrist pins 23 and 23' respectively, which preferably are provided with rollers 24 and 24' respectively. The wrist pins extend laterally from the arms into suitable guide ways 25 and 25' or 26 and 26' formed in the plates 27 and 27' which are secured to the inner sides of the upright sides 6 and 7 of the case, said guides having been described in said prior applications for Letters Patent.

As illustrated, the extent or degree of the stepping of the leaves in normal position is somewhat less than the thickness of a leaf 60 or frame, and it will be apparent that if a greater degree of stepping is desired with a greater degree of movement of the leaves on the hinge bars, this will be accomplished by the use of larger segments and placing 65 the rack bars farther rearward on the

leaves. The rear segments, as will be seen, are pivotally connected both to the hinging ears 13 and 13' and also to the hinging bars 15 and 15', there being relatively few wearing parts in which lost motion may occur. The fronts of the upper portions of the leaves have suitable indexing characters thereon as 28, 28', as is customary.

The sides 6 and 7 are provided on the inner sides thereof with a pair of inclined channel guide ways 29 and 29' in which is mounted an abutment preferably comprising two main parts 30 and 30', one provided with rollers 31 and 31' and the other with rollers 32 and 32', the main parts having upwardly extending arms 33 and 33' thereon which prevent the leaves from tilting rearward in vertical position, the abutment being operatively connected with the leaves. The main parts of the abutment are provided with pivots 34 and 34' to which coupling bars 35 and 35' are connected, each bar having a hook 36 on its end that engages a wrist pin 14'' preferably formed as an extension on the rearmost hinge pins 14 and 14' that connect the two rearmost leaves together, the coupling bars resting on stops 37 and 37' when not in use, the stops being fixed on the abutment. The two main parts of the abutment are connected together by means of a rod 38.

It will be understood that the controlling arms 22 and 22' may extend from the segments 20 and 20' respectively at various angles, the guides for the arms being arranged accordingly as may be required; and various other details of construction may be varied within the scope of the appended claims.

In practical use, the leaves being normal in echelon in upright position, all or any number of the leaves may be drawn forward to prone position in order to gain access to the papers filed on the leaves, and during the forward movement while the leaves are carried upon pivots 12 and 12', controlling arms 22 and 22' are guided by means of the guide ways in the plates secured to the sides of the case, each leaf excepting the foremost one being supported when in upright position directly by means of the gear segments and the rack bars, as will be readily understood, the gear segments being prevented from rotating on their pivotal supports by means of their controlling arms and the guide ways therefor, so that as will be seen the leaves on approaching prone position are drawn toward their pivotal supports so as to form a rectangular pack, and on approaching upright position are forced away from their pivotal supports so as to stand in echelon. The leaves when upright are inclined by the force of gravity to lean rearward against the abutment which holds them accurately in vertical position, as will 180

- be understood. When it is desired to remove the leaves from the case the abutment is disconnected therefrom and permitted to rest against the back of the case, the leaves being first drawn forward to form a rectangular pack and then lifted from the pivot bearings 8 and 8'. Having thus described the invention what is claimed as new, is—
- 10 1. A credit accounting register including a frame provided with a plurality of rack-bars, a plurality of hinge-bars movably connected with the frame, and a plurality of gear segments pivoted to the hinge-bars and 15 engaging the rack-bars.
- 15 2. A credit accounting register including a frame provided with a plurality of fixed bars having gear teeth, a plurality of hinging devices movably connected with the 20 frame adjacent the fixed bars, and a plurality of segments pivoted to the hinging devices and having gear teeth thereon engaging the gear teeth of the fixed bars, each segment having a controlling arm thereon.
- 25 3. A credit accounting register including a case, a plurality of normally upright leaves, hinging devices connecting the leaves together and permitting relative vertical movement of the leaves, pivots supporting 30 the foremost one and thereby the remaining ones of the leaves in the case, and a plurality of coöperating series of toothed gearing, each series connected with two adjacent leaves for normally supporting the rearward 35 one on the forward one of the two leaves in echelon and preventing their relative vertical movement.
- 40 4. A credit accounting register including a plurality of leaves provided each with a plurality of toothed bars, a plurality of hinging devices movably connected with the leaves and pivotally connected with adjacent leaves, and a plurality of toothed segments pivotally connected with the hinging 45 devices and meshing with the toothed bars, each segment having a controlling arm thereon.
- 45 5. A credit accounting register including a plurality of leaves, one leaf of each two adjacent leaves having a toothed rack-bar thereon, the other one of the two adjacent leaves having a toothed gear segment pivotally connected thereto and meshing with the next adjacent rack-bar, the segment being provided with a controlling arm, and adjustably movable means connecting the adjacent leaves together.
- 55 6. A credit accounting register including a case comprising sides, guideways on the sides, and a plurality of leaves of which the foremost is pivotally supported in the case, each leaf excepting the foremost one having a pair of toothed rack-bars fixed thereon and having also a pair of relatively movable hinge members, the hinge members being
- 70 pivotally connected to the next adjacent forward leaves, each leaf excepting the rearmost one having a pair of toothed segments pivotally connected thereto that mesh with the rack-bars of the next adjacent rearward leaves, the segments having controlling arms thereon that are guided in the guideways.
- 75 7. In a filing appliance, the combination of a plurality of leaves or frames having each a supporting bar rigidly fixed thereon and provided with a segment movably connected with the leaf or frame to coöperate with the bar for adjustment of the leaf or frame relative to the segment, the segments being pivotally connected with next adjacent leaves for support.
- 80 8. In a filing appliance, the combination of a plurality of leaves or frames provided each with a plurality of coöperating toothed devices for normally supporting the leaf in upright position, one of the devices being rotatably connected with the leaf or frame to move longitudinally thereof and rotatably supported by an adjacent leaf or frame, and a plurality of independently guided controlling devices connected with and controlling the rotatably supported devices respectively.
- 85 9. In a filing appliance, the combination with a plurality of normally upright leaves or frames, movable means pivotally connecting the leaves or frames together and permitting relatively vertical movement thereof, and means for pivotally supporting the foremost one of the leaves or frames 90 adapted for bodily supporting the remaining leaves or frames in normal position, of a plurality of coöperating rack and segment devices carried by the leaves or frames, one of the devices being rotatably supported 95 by its carrying leaf or frame relatively thereto and bodily supporting the coöperating device and its carrying leaf or frame when the latter is in normal position, the rotatably supported devices being provided 100 respectively with controlling devices.
- 100 10. In a filing appliance, the combination of a plurality of leaves, hinging devices connecting the leaves together and having adjusting movement longitudinally of the leaves, pivots for supporting the foremost one of the leaves, and a plurality of coöperating series of toothed gearing, each series being connected with two adjacent leaves for supporting the rearward one of 115 the two leaves and controlling the adjustability of the hinging devices.
- 115 11. In a filing appliance, the combination of a plurality of frames provided each with a rack-bar, a plurality of hinge-bars movably connected respectively with the frames and pivotally connected with adjacent frames, a plurality of gear segments pivotally connected to the said adjacent frames and engaging the adjacent rack-bars respectively, and 120
- 125 12. In a filing appliance, the combination of a plurality of frames provided each with a rack-bar, a plurality of hinge-bars movably connected respectively with the frames and pivotally connected with adjacent frames, a plurality of gear segments pivotally connected to the said adjacent frames and engaging the adjacent rack-bars respectively, and 130

guideways fixedly arranged at opposite sides of the frames for controlling the movement of the gear segments.

12. In a filing appliance, the combination of a plurality of frames provided each with a rack-bar, a plurality of hinge-bars movably connected respectively with the frames, a plurality of gear segments pivoted to the hinge-bars and engaging the rack-bars re-

spectively, and means for controlling the movement of the gear segments.

In testimony whereof, I affix my signature in presence of two witnesses.

ELLIS T. SILVIUS.
